UNITED STATES PATENT OFFICE.

JOHN L. WEBB AND GEORGE W. WISEMAN, OF SAWTELLE, CALIFORNIA; SAID WEBB
ASSIGNOR TO SAID WISEMAN.

DOOR-STOP.

1,098,307.

Specification of Letters Patent.

Patented May 26, 1914.

Application filed August 5, 1913. Serial No. 783,187.

To all whom it may concern:

Be it known that we, JOHN L. WEBB and GEORGE W. WISEMAN, residing at Sawtelle, in the county of Los Angeles and State of California, have invented a new and useful Door-Stop, of which the following is a specification.

Our invention relates to stops which are attached to doors for the purpose of restraining them in the open position or partly open position.

The principal object of our invention is to provide a device of this character which will be simple to construct and which will maintain an even pressure upon the floor even where the floor has considerable irregularities thereon.

Other objects and advantages will appear hereinafter.

20 Referring to the drawings, which are for illustrative purposes only: Figure 1 is a portion of a door and a casing therefor, the door having our invention applied thereon. Fig. 2 is a side elevation partly in section of our 25 invention as applied to a door, taken on line x^2-x^2 on Fig. 1. Fig. 3 is a perspective view of our invention shown detached from the door. Fig. 4 is a detail showing the method of fastening some of the parts.

30 In the form of our invention illustrated in these drawings 10 is a slide formed of sheet metal and consisting of walls 11 and 12 and a back 13. The lower end of the walls 11 and 12 contain a soft rubber block 14, 35 which is held in place by a clamping plate 15, this clamping plate being fastened into the walls 11 and 12 by small riveted portions 16 which extend therethrough and are suitably expanded at the outer edge. On the 40 opposite end from the rubber block 14 the walls 11 and 12 are crimped in as shown at 17. The slide 10 is carried in the cover 18 which is formed of walls 19 and 20 and a back 21 and a top 22. The walls 19 and 20 45 are bent outwardly to form ears 23 and 24 and crimped inwardly at 25 and 26 to form lugs to guide and restrain the walls 11 and 12 of the slide 10. The ears 23 and 24 are provided with holes 27 through which 50 screws 28 may be driven for the purpose of fastening the door stop to the door. The clamping plate 15 is provided with a top 29 which has a slot 30 therein. A rod 31 having a slot 32 therein slips into and engages 55 the top 29 of the clamping plate 15. This

rod extends upwardly through the top 22 of the cover 18 and a spring 33 is placed around the rod 31 engaging the top 29 and the top 22 and tending to force the top 29 downwardly when the cover 18 is secured to 60 the door. The ends 17 are crimped outwardly a sufficient distance to prevent them passing by the lugs 25 thus limiting the downward movement of the rod 31 under the influence of the spring 33. The rod 65 31 extends upwardly through a bracket 34 which is fastened to the door and to which is loosely attached a clutch 35, the hole in this clutch 35 being slightly larger than the rod 31. The clutch 35 passes over the 70 bracket 34 being provided with an intersecting portion 36 for this purpose. The upper end of the rod 31 is provided with an eye 37.

The method of operation of our invention is as follows: The cover 18 is fastened to a 75 door 38 by means of the screws 28 in such a position that the rubber block 14 may be raised sufficiently high to clear the floor 39. The bracket 34 is also fastened to the door. The spring 33 tends to force the rubber 80 block downwardly, but this action is resisted by the clutch 35 which is tilted by the projections 36 extending over the bracket 34 in the position shown in Fig. 2. In this position the rod 31 is firmly gripped and restrained as shown in Fig. 2. The door is then opened the desired distance and the clutch 35 is tripped by lifting upwardly on the outer end thereof in the direction shown in the arrow in Fig. 2. This removes the restraint from the rod 31 which is forced downwardly by this spring 33 and causes the rubber block 14 to press firmly against the floor, thus restraining the door 38 in whatever position it may be set for. When 90 it is desired to change the position of the door, a finger is slipped through the eye 37 and the rod 31 is pulled upward. When it is moved upward a certain distance and is released the clutch 35 is dropped and again 100 restrains the rod holding the rubber block 14 away from the floor.

We claim as our invention:

A door stop adapted to secure the door in any position comprising a cover of rectangular cross-section provided with ears for fastening to the door and the crimped portions extending upwardly in the body thereof, a slide of approximately rectangular cross-section fitting tightly into and movable in said 110

cover, bent portions on said slide adapted to engage with the crimped portions on said cover to prevent said slide from passing entirely out of said cover, a friction block at the lower end of said slide, a rod attached to said slide extending upwardly through said cover, a spring surrounding said rod and adapted to press said friction block against the floor, a bracket adapted to be fastened 10 to the door and to surround and guide said rod and a clutch coöperating with said

bracket to restrain said rod in the compressed position of said spring.

In testimony whereof, we have hereunto set our hands at Los Angeles, California, 15 this 30th day of July, 1913.

JOHN L. WEBB.
GEORGE W. WISEMAN.
